IMPROVEMENT IN STEAM-GENERATOR HEATERS.

THOMAS E. BELTON, OF BUFFALO, NEW YORK.

Letters Patent No. 60,124, dated December 4, 1866.

SPECIFICATION.

TO ALL WHOM IT MAY CONCERN:

Be it known that I, THOMAS E. BELTON, of the city of Buffalo, in the county of Erie, and State of New York, have invented a new and improved Heater for Steam Boilers; and I do hereby declare that the following is a full and exact description thereof, reference being had to the accompanying drawings, making part of this specification, in which—

Figure 1 is a cross-section of the heater in the plane of line $x x$, fig. 2.

Figure 2 is a central longitudinal section of the same, in the plane of line $y y$, fig. 1.

Like letters of reference designate corresponding parts in both figures.

My improvements are designed more especially for use with marine boilers and those employed in navigating rivers where the deposit of mud and other sediment is considerable, which requires frequent blowing off in order to prevent undue accumulation of the same; and the invention consists in the construction and arrangement of the heater relative to the boiler and furnace; in a device for facilitating the discharge of the sedimentary deposit; and also an arrangement for preventing the excessive heating and injury to the portions exposed to the fire when the vessel is careened, all as hereinafter fully set forth.

As represented in the drawings, A is the furnace, B the fire grate, C the front end of the boiler, D the crown sheet, and E the steam dome. F represents the heater, which is preferably of cylindrical form, and situated, preferably, just back of the bridge of the furnace, transversely of the same, as shown, so that the heat may circulate freely around it and through the horizontal transverse flues, $g g$, with which it is provided. At each end of the bottom of the heater, and extending about one-third of its length, is a hollow bridge or sediment passage, H, closed at the extreme ends, with its two sides inclined toward each other, forming an angle at the top like roof, as represented in fig. 1. These sides, at their lower edge and junction with the bottom of the heater, are provided with small openings, $i i$, for the flow of the mud or other deposit into the passage, H, where it is discharged through the throat or pipe, J, in the bottom, which is provided with suitable stop-cock, k. The aggregate size of the openings, $i i$, should be a little less than that of the exit pipe J, in order to produce a greater suction and more rapid current through them during the blowing off, and thereby facilitate the discharge of the sediment. The water for the boiler is supplied to the heater by means of a force pump, through the main feed-pipe, I, provided with a check-valve, l, which opens up through the centre of the bottom of the heater. Across the bottom of the heater, between the bridges, H, is fastened a horizontal distributing-plate, m, against the under side of which the injected stream of water diffuses itself, whence it gradually commingles at each end of the plate with the heated water in the vessel. At the top of the heater, at each end, portions are cut away so as to form (preferably) long oval apertures, $n n$, which form the base and open upward into conical passages, O, the apices of which are connected with the crown sheet, D, by means of the short pipes, $p p$, that open into the boiler above. The object of these enlarged conical passages is to protect the heater from injury under the following circumstances: while in a sea-way, or at dock receiving and discharging cargo, the vessel is consequently careened, in consequence of which the heater is longitudinally inclined, so that one end is elevated above the other and above the water line. The result of this is that the raised end becomes excessively heated from containing only steam and being exposed to the great heat of the furnace. When the vessel rights itself there is a sudden rush of the water to this end, the lower temperature of which would frequently cause the top of the heater to crack from sudden cooling, were it constructed closed at this point with only a passage at the centre. By constructing the top of the heater with the enlarged conical passages leading to the ejection pipes, $p p$, steam cannot accumulate in the angle of the elevated end of the heater when inclined, and consequently the liability to overheating is obviated; and the form thus given to the parts connected with the pipes, $p p$, admits of greater freedom of expansion and contraction, from the intensity and extremes of temperature to which the heater is subjected, without straining the joints. When the vessel is not going it is frequently desirable to keep up sufficient heat to prevent the steam in the boiler from going down. At such times as the machinery is not working and the heater is not supplied by the pump through the supply-pipe, I, I provide an additional pipe, q, for communicating with the water in the leg, e' , of the boiler, through which the heater may receive its supply to compensate for what has evaporated, the water from the leg flowing in as the temperature of that in the heater is raised above that of the boiler, thus creating a continuous circulation.

With marine boilers, where the use of salt water makes it necessary to blow off frequently, the employment of a heater is a matter of great importance, to keep the feed-water of the boiler at a boiling temperature in

order to maintain the temperature and keep the steam from going down, which would otherwise result from the blowing off were the feed-water introduced cold.

With river boilers the heater, and the device at the bottom of the same for blowing off the mud and other sediment which so abounds, are attachments of equal if not greater importance, for the sediment is discharged with greater facility from the heater, which prevents its passage into the boiler, where it would have to be blown off with greater difficulty and a more detrimental effect. The turbid water as it enters the heater strikes the under side of the plate, *m*, which arrests and deflects it each way toward the bottom, where the greater portion of the sediment settles and is blown off through the shields and pipes, *H J*.

The pump of the main feed-pipe, *I*, which supplies the heater, may be operated by a donkey engine, so that the water shall at all times enter the boiler hot. The transverse flues, *g g*, being in a direct line of the draught, through which the fire passes, are subject to an intense heat, the large surface of which, thus exposed, rapidly heats the water in contact therewith.

What I claim as my invention, and desire to secure by Letters Patent, is—

The heater *F*, provided with flues *g g*, and conical discharge-ports *O O*, arranged in combination with a boiler and furnace so as to operate substantially as set forth.

I also claim the mud-shields *H H*, provided with perforations *i i*, in combination with the pipes *J*, for discharging the mud and other sediment, substantially in the manner specified.

I also claim the deflecting and distributing-plate *m*, arranged and operated as described.

I also claim, in combination with the heater *F*, constructed as described, and leg *e* of the boiler, when the same extends below the level of said heater, the pipe *q*, arranged and operating substantially in the manner and for the purpose herein set forth.

In witness whereof I have hereunto signed my name in the presence of two subscribing witnesses.

THOS. E. BELTON.
